UNITED STATES PATENT OFFICE.

CLARENCE A. BODDIE, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL MEASURING INSTRUMENT.

1,206,406.

Specification of Letters Patent. Patented Nov. 28, 1916.

Application filed December 4, 1915. Serial No. 65,012.

To all whom it may concern:

Be it known that I, CLARENCE A. BODDIE, a citizen of the United States, and a resident of Pittsburgh, in the county of Allegheny and State of Pennsylvania, have invented a new and useful Improvement in Electrical Measuring Instruments, of which the following is a specification.

My invention relates to electrical-measuring instruments and particularly to maximum-demand wattmeters.

The object of my invention is to provide a meter of the above indicated character having means for periodically resetting a portion of the mechanism thereof in order to obtain a true indication of the maximum demand.

My copending U. S. application, Serial No. 687,395, filed March 30, 1912, discloses a maximum-demand wattmeter comprising a main and an auxiliary armature actuated by a common field magnet and having a mechanism interposed therebetween to permit one armature to control the operation of the other.

In my present invention, I provide an instrument substantially the same as set forth in the above entitled application, and I further provide means whereby a portion of the windings on the magnetizable core member may be periodically open-circuited to permit one of the armatures to return to its initial position. This is accomplished by the use of a contact-making and breaking device that is adapted to open the circuit when the torque of the control spring is substantially the same as the torque of the armature. The balanced-torque condition is obtained recurrently, and hence, serves as a convenient and desirable timing period for the resetting of one of the armatures.

Figure 1 of the accompanying drawings is a diagrammatic view, partially in elevation and partially in section, of a maximum-demand meter embodying my invention, and Fig. 2 is a detail plan view of a portion of the mechanism embodied in the maximum-demand meter shown in Fig. 1.

An electric circuit 1 is provided with a current transformer 2 and a potential transformer 3. The secondary winding 4 of the current transformer 2 is operatively connected to the current windings 5 that surround portions of the magnetizable core

member 6 of a maximum-demand meter 7. The secondary winding 8 of the potential transformer 3 is connected to the potential windings 9 that also surround portions of the magnetizable core member 6. A contact-making and breaking device 10 is connected in circuit with the windings 8 and 9 for the purpose of controlling the circuit thus constituted and, consequently, for effecting the resetting of the meter, as hereinafter more fully set forth.

The meter 7 is provided with a main armature 11 and an auxiliary armature 12 that are disposed in the air gap 13 of the magnetizable core member 6 and are subjected to similar actuating forces in accordance with the energy which traverses the windings 5 and 9. The auxiliary armature 12 is mounted on a shaft 14 that is also provided with an eccentric 15 which is adapted to oscillate a double palette 16 the teeth of which are adapted to engage the teeth of an escapement wheel 17. The escapement wheel 17 is mounted on a shaft 18 that is also provided with a pinion 19. The main armature 11 is mounted on a shaft 20 that has a gear wheel 21, one arm 22 of the contact-making and breaking device 10 and one end of a control spring 23 also mounted thereon, the other end of the control spring 23 being attached to a stationary member 24. A sleeve 25 that loosely surrounds the shaft 20 is provided with a ratchet wheel 26 and a gear wheel 27. The pinion 19 is adapted to engage the gear wheel 27, and the gear wheel 21 is adapted to engage a gear wheel 28 that is mounted on a shaft 29. A second gear wheel 30 is also mounted on the shaft 29 and is adapted to engage a gear wheel 31 that is mounted on a shaft 32 upon which is also mounted a dog 33. The dog 33 is adapted to actuate a shaft 34 upon which is mounted a pointer 35.

The contact-making and breaking device 10 comprises a member or arm 22 that is securely mounted on the shaft 20, a resiliently supported contact member 36, a lever arm 37 that is loosely mounted on the shaft 20 and a pawl 38 that is pivotally mounted on the arm 37 and adapted to engage the teeth of the ratchet wheel 26. The lever arm 37 is provided with a projection 39 that carries a contact member 40 and one end of a relatively light helical spring 41, the other end of which is attached to the

member 22. The member 22 is provided with a bracket or L-shaped projection 42 for the purpose of actuating the lever 37 when it is moved in a clock-wise direction. 5 The lever arm 37 is provided with a relatively heavy member 43 on one end thereof for purposes hereafter more fully set forth.

When the contact members 36 and 40 are engaged, and current traverses the circuit 1, 10 the armature 12 will rotate in accordance with the energy traversing the circuit, and the armature 11 will tend to turn against the action of the spring 23 with a speed that is controlled by the speed of the armature 15 12. That is, the armature 11 moves the arm 22 which compresses the spring 41 to thereby move the arm 37, but the degree of movement of the arm 37 is controlled by the armature 12 through the pawl 38, the 20 ratchet wheel 26, gear wheel 27, pinion 19, the escapement wheel 17 and the double pallette 16. When the armature 11 turns, it actuates the pointer 35 through the gear wheels 21, 28, 30 and 31 and the dog 33 to 25 thus indicate the maximum demand of energy traversing the circuit 1 during predetermined time intervals.

Since it is desirable to recurrently reset the armature 11, the spring 41 is of such 30 proportions that, when the torque of the spring 23 is equal to the torque of the armature 11, the spring 41 is permitted to expand to effect disengagement of the contact members 36 and 40 which opens the 35 circuit of the potential winding 9 and thus removes the actuating force from the armature. When the circuit of the winding 9 is interrupted, the spring 23 turns the arm 22 which, through the bracket 42, carries 40 the arm 37 in a clock-wise direction until the arm 22 engages the stationary member 24. When the armature 11 is being returned to its initial position, the arm 37 generates a momentum because of the movement of 45 the relatively heavy member 43 which compresses the spring 41 a sufficient amount, after the arm 22 has engaged the stationary member 24, to effect engagement of the contact members 36 and 40 and to cause the 50 pawl 38 to engage a tooth that will retain the contact members 36 and 40 in engagement. Thus, the circuit of the potential winding 9 is again completed and the armature 11 will again be permitted to rotate 55 counter clock-wise until the torque generated thereby is neutralized by the torque of the spring 23. When the armature 11 is returned to its initial position, the dog 33 is also returned to its initial position, leaving 60 the pointer 35 to indicate the maximum demand. The pointer will remain in this position until it is either reset manually or advanced by the mechanism when the maximum demand is increased.

65 My invention is not limited to the par-

ticular structures illustrated, as many modifications may be made therein without departing from the spirit and scope of the invention as set forth in the appended claims.

I claim as my invention:

1. In an electrical-measuring instrument, the combination with two movable armatures and a single means for simultaneously actuating the same, of means interposed between the said armatures whereby one controls the operation of the other, means for yieldingly opposing the movement of one armature and for returning the said armature that is opposed in its movement to its initial position when its resultant torque is substantially zero. 70

2. In an electrical-measuring instrument, the combination with two movable armatures and a single means for simultaneously actuating the same, of means interposed between the said armatures whereby one controls the operation of the other, means for opposing the movement of one armature and means for open-circuiting the actuating means when the torque of the armature is substantially zero. 85

3. In an electrical-measuring instrument, the combination with two movable armatures and a single means for simultaneously actuating the same, of means interposed between the said armatures whereby one controls the other, resilient means for retarding the operation of one armature, and means controlled by the said retarded armature for open-circuiting the actuating means when the torque of the resilient means neutralizes the torque of the armature. 100

4. In an electrical-measuring instrument, the combination with two movable armatures and a single means for simultaneously actuating the same, of a spring for opposing the operation of one armature, and means controlled by the spring-opposed armature for open-circuiting the actuating means when the torque of the spring neutralizes the torque of the armature. 105

5. In an electrical-measuring instrument, the combination with two armatures and a single means for simultaneously actuating the same, of means interposed between the armatures whereby one controls the operation of the other, and means for periodically returning one of the armatures to its initial position. 115

6. A wattmeter comprising two armature members, means for simultaneously applying similar actuating forces thereto, means whereby one of the armature members controls the operation of the other armature members, and means for periodically interrupting the actuating forces. 125

7. A wattmeter comprising a main and an auxiliary armature, means for simultaneously actuating the same, a spring for op- 130

posing the operation of the main armature, means actuated by the auxiliary armature for controlling the operation of the main armature, a contact-making and breaking device actuated by the main armature for controlling the circuit of the actuating means to thereby permit the spring to periodically reset the main armature.

8. A wattmeter comprising a main and an auxiliary armature, means for simultaneously actuating the same, a spring for opposing the operation of the main armature, means actuated by the auxiliary armature for controlling the operation of the main armature, a contact-making and breaking device actuated by the main armature for controlling the circuit of the actuating means to thereby permit the spring to reset the main armature when the torque of the main armature is equal to the torque of the spring.

9. A wattmeter comprising a main and an auxiliary armature, electromagnetic means for simultaneously actuating the armatures, a spring for opposing the operation of the main armature, means actuated by the auxiliary armature for controlling the forward operation of the main armature, and a contact-making and breaking device actuated by the main armature and adapted to open the circuit of the electromagnetic means when the torque of the main armature is neutralized by the torque of the spring to thereby permit the main armature to return to its initial position.

35 10. A wattmeter comprising a main and an auxiliary armature, electromagnetic means for simultaneously actuating the armatures, a spring for opposing the operation of the main armature, means actuated by the auxiliary armature for controlling the forward operation of the main armature, and a contact-making and breaking device actuated by the main armature and adapted to open the circuit of the electromagnetic means when the torque of the main armature is neutralized by the torque of the spring to thereby permit the main armature to return to its initial position, said contact-making and breaking device being adapted to close the circuit after the main armature has returned to its initial position.

11. In an electrical measuring instrument, the combination with two movable armatures and means for simultaneously actuating the same, of means whereby one armature controls the movement of the other, means for yieldingly opposing the operation of one armature, and means for open-circuiting the actuating means under predetermined conditions.

12. In an electrical measuring instrument, the combination with two movable armatures and means for simultaneously actuating the same, of means whereby one armature controls the movement of the other,

means for yieldingly opposing the operation of one armature, and means for periodically rendering the actuating means under predetermined conditions.

13. In an electrical measuring instrument, the combination with two movable armatures, and a single means for simultaneously actuating the same, of means whereby one armature controls the movement of the other, means for yieldingly opposing the operation of one armature, and means for periodically rendering the actuating means ineffective.

14. In a measuring instrument, the combination with two movable members and means for simultaneously actuating the same, of means whereby one movable member controls the other, a spring for opposing the operation of one of the movable members, and means for rendering the actuating means ineffective when the torque of the spring-opposed member is neutralized.

15. In a measuring instrument, the combination with two movable members and a single means for simultaneously actuating the same, of means whereby one of the movable members controls the operation of the other, means for periodically rendering the actuating means ineffective, and means for returning one of the movable members to its initial position when the actuating means is rendered ineffective.

16. In a measuring instrument, the combination with two movable members and means for simultaneously actuating the same, of means whereby one member controls the other, means for yieldingly opposing the movement of one member, and means for open-circuiting the actuating means when the torque of the member that is opposed in its movement reaches a predetermined value.

17. In a measuring instrument, the combination with two movable members, and means for simultaneously and independently actuating the same, of means whereby one controls the movement of the other, a spring for opposing the operation of one of the movable members, and means for periodically rendering the actuating means ineffective to permit the spring to return one of the movable members to its initial position.

18. In a measuring instrument, the combination with an armature, means for actuating the armature, and an indicating mechanism adapted to be actuated by the armature, of a spring for opposing the operation of the armature, and means for periodically open-circuiting the actuating means to permit the resetting of a portion of the indicating mechanism.

19. In an electrical measuring instrument, the combination with a movable member and means for actuating the same, of

means for yieldingly opposing the operation of the movable member, and means for open-circuiting the actuating means under predetermined conditions to permit the movable member to return to its initial position.

20. In an electrical measuring instrument, the combination with a movable member and means for actuating the same, of means for yieldingly opposing the operation of the movable member, means for controlling the operation of the movable member, and means for open-circuiting the actuating means under predetermined conditions to permit the movable member to return to its initial position.

21. In a maximum demand meter, the combination with an armature, means for actuating the armature and an indicating mechanism adapted to be actuated by the armature, of means for controlling the operation of the indicating mechanism, a spring for opposing the operation of the armature, and means for rendering the actuating means ineffective under predetermined con-

ditions to permit the spring to reset a portion of the indicating mechanism.

22. In a measuring instrument, the combination with two movable members and means for actuating the same, of means whereby one member controls the other, means for yieldingly opposing the movement of one member, and means for open-circuiting the actuating means when the torque of the member that is opposed in its movement reaches a predetermined value.

23. In an electrical measuring instrument, the combination with a movable armature and means for actuating the same, of means for controlling the movement of the armature, means for opposing the operation of the armature, and means for periodically rendering the actuating means ineffective to permit the said opposing means to reset the said armature.

In testimony whereof, I have hereunto subscribed my name this 30th day of Nov. 1915.

CLARENCE A. BODDIE.
